UNITED STATES PATENT OFFICE.

CHARLES W. LEMASTER, OF CENTRAL CITY, NEBRASKA.

DESIGN FOR A BADGE.

SPECIFICATION forming part of Design No. 26,016, dated September 15, 1896.

Application filed March 16, 1896. Serial No. 583,472. Term of patent 31 years.

To all whom it may concern:

Be it known that I, CHARLES W. LEMASTER, a resident of Central City, in the county of Merrick and State of Nebraska, have invented 5 a certain new and useful Design for Badges; and I do hereby declare that the following is a full, clear, and exact description thereof, reference being had to the accompanying drawings, and to the letters of reference marked 10 thereon, which form a part of this specification.

Referring now to the drawings, the Figures 1 and 2 thereof represent a badge shaped 15 in accordance with my new design in face or plan view and in transverse vertical section, respectively.

The drawings may be considered as representing a metal button adapted to be inserted 20 in a buttonhole, designed to be worn as a badge, though the same design may obviously be embodied in a print or painting upon ribbon or other fabrics, to be worn as a badge, or upon a banner, float, or the like, carried 25 in the usual manner. When designed for use as a metal badge, other well-known means of attachment may obviously be employed in place of the button back and shank shown.

The design is primarily intended as having 30 a political significance, and its essential features are the representation of the novel bug herein shown, bearing upon its back the words and characters "Free, Unlimited, 16 to 1," the main or principal part of the bug bearing the numeral "16," and the words 35 "Free" and "Unlimited" being made of, or to represent, the metal silver, while that part bearing the numeral "1" will be made of, or to represent gold, so that the full significance of the design will be "Silver-Bug," in favor 40 of 'free, unlimited' coinage of silver in the proportions of sixteen parts silver to one part of gold." The difference in color between the silver and gold is indicated in the present instance by the darker or heavier shading of the gold part of the design.

The bug herein shown is of fanciful design, comprising as its main features an elongated oval body, a shield-shaped thorax, and a head which has the form of a pair of circular or parti-spherical protuberances arranged 5 side by side. The eyes consist of two small spherical protuberances projecting from the front side of the head and set widely divergent. From near the center of the head a single pair of feathered *antennae* project forwardly, the outer ends of which are curved 10 gracefully divergently outward and form spirals. The legs, of which there are three in each side, are made thicker or more stocky than natural and are each bent at a point near the body of the bug, so as to extend rearwardly close alongside of the body. The central part of the body is shown as covered by two short shell-like wings or *elytra*, which have gracefully-rounded margins and meet 15 at the median line of the insect, their length being such as to leave approximately one-third of the posterior part of the body uncovered. The right wing represents gold and bears the numeral "1," while the left wing, bearing the numeral "16," and the remainder of the body represent silver. The word "Free" is printed or impressed upon the anterior silver portion of the body in advance of the wings, and the word "Unlimited" upon the posterior silver portion in rear of the wings, so that the whole effect of the design and its symbolization may be taken in at a single glance.

I claim—

The design for a badge, substantially as shown and described.

In testimony that I do claim the foregoing as my own invention I hereto affix my own signature, in presence of two witnesses, this 5th day of March, A. D. 1896.

CHARLES W. LEMASTER.
